(57) **CLAIM**

(21) Appl. No.: **29/119,163**

I claim the ornamental design for shadow box belt buckle
with clouser's deep minnow, silver shiner, as shown and
described.

(22) Filed: **Feb. 24, 2000**

DESCRIPTION

(63) Continuation-in-part of application No. 29/100,194, filed on
Feb. 4, 1999.

The dominant feature of the invention resides in the design
of a belt buckle featuring a miniature shadow box belt
buckle with clouser's deep minnow, silver shiner, fixed in
lucyte imbedment in the manner of a shadow box.

(51) **LOC (7) Cl. 02-07**

FIG. 1 is a perspective view of a shadow box belt buckle
with clouser's deep minnow, silver shiner showing my new
design;

(52) **U.S. Cl. D11/232**

FIG. 2 is a top plan view thereof;

(58) **Field of Search D11/200-220,**

FIG. 3 is a left side elevational view thereof the right side
being a mirror image thereof;

D11/232, 224, 241, 69; 24/199, 170, 200,
30.5 R, 614, 616, 625, 615, 650; 63/20

FIG. 4 is a cross section view shown along lines 4—4 of
FIG. 2; and,

FIG. 5 is a bottom elevational view thereof.
